UNITED STATES PATENT OFFICE.

JOHN PEARSON, OF CHICAGO, ILLINOIS.

JOURNAL-BOX.

No. 852,032.

Specification of Letters Patent.

Patented April 30, 1907.

Application filed May 2, 1906. Serial No. 314,751.

To all whom it may concern:

Be it known that I, JOHN PEARSON, a citizen of the United States, residing at Chicago, in the county of Cook and State of Illinois, have invented certain new and useful Improvements in Journal-Boxes, of which the following is a specification, reference being had therein to the accompanying drawings.

This invention relates to improvements in car journal boxes, and it consists of the organizations and arrangements of parts hereinafter described and then pointed out in the appended claims.

In the accompanying drawings—Figure 1 is a view in front elevation of a car journal box constructed in accordance with my invention and showing a portion of the lid broken out to disclose the lid-spring and cams coöperating therewith; Fig. 2 is a vertical sectional view of the device of Fig. 1, showing in full lines the lid in its closed position and in dotted lines in its partially open position; Fig. 3 is a similar view showing the lid entirely open; Fig. 4 is a detail fragmentary side view of the box; Fig. 5 is a view illustrating a modification; and Fig. 6 is a sectional view similar to Fig. 2 showing a further modification of the invention. Fig. 7 is a detail view showing the button and lug on the lid for the spring, together with a modified form of spring.

The journal box 10 may be of the usual or any preferred construction, except in the particulars hereinafter specified, and is provided with the usual front opening which is closed by a lid 11.

The present invention has particular reference to the hinge connection between the lid and journal box and also the spring for holding the lid in its opened and closed positions.

The top of the box 10 is provided at its front above the box opening with a hinge lug 12. As shown in Figs. 2 and 5, the upper face of the hinge lug 12 is curved in transverse vertical section. This lug 12, in the construction illustrated in Figs. 1 to 4, inclusive, is provided with a vertically elongated opening 13 extending transversely of the box, which opening is substantially oval in shape except that it is provided at its bottom at the side toward the front of the box with an angular shoulder 14 extending the length of the opening 13 and the purpose of which will be hereinafter explained. As the

lid in this construction is designed to be moved vertically during the initial opening movement, the height of the opening 13 is at least that of the movement of the lid during the vertical movement referred to. 60

The hinge lug 12 is provided on its curved face and at the front with a pair of opposite shoulders 15. In the present instance such shoulders are about 90 degrees in length, extending upwardly from substantially the horizontal axis of the lug 12 and being curved to conform to the curvature of the lug 12 as clearly shown in Fig. 2. The shoulders 15 at their adjacent sides are provided with opposing cam faces *a* converging upwardly, opposing cam faces *b* diverging upwardly from the upper ends of the cam faces *a*, and merging into parallel opposing end faces *c*. The meeting point or crown of the cam faces *a* and *b* at each side of the box is 75 slightly rounded, as shown in Fig. 1. With this arrangement the shoulders provide a groove the side walls of which first tend to converge, then diverge and finally terminate in an end portion with the side walls parallel. 80

The lid 11 is formed with a hollow enlargement or hood 16 at its upper part and the side walls of this hood are provided with hinge lugs 17 having alined apertures to receive the pintle or hinge pin 18, which pin also passes through the opening 13 as shown in Fig. 2. The rear end of the hood is bent inwardly, as at 19, so as to practically abut against the hinge lug and prevent the ingress 90 of dust at this point when the lid is closed.

The hinge pin 18 is circular in cross section except for a longitudinal segmental recess 20 corresponding substantially to the shape of the shoulder 14 for which it provides a clearance, as shown in Fig. 2, and which when the lid is closed, straddles the shoulder but does not rest thereon. The openings in the hinge lugs 17 are of the same cross sectional shape as the pin 18, as shown in Fig. 4, so that the pin is compelled to turn with the lid when the latter is swung to open or close the box. 95

The lid 11 is provided near the lower end of the hood 16 with a transversely disposed button 21, the shank of which is curved cross-sectionally on its lower face as shown in Fig. 1, and the head of which extends laterally on both sides of the shank as shown in Fig. 7. A lug 23 projects from the lid under the button 21, and its upper face is substan- 110

tially concentric with the curved face of the button shank. A U-shaped spring 24, which is shown as formed of a strip of metal rectangular in cross-section, is seated between the 5 button shank and the lug 23 and held from displacement either laterally or rearwardly by the button 21. The lug 23 prevents the spring from dropping downwardly. The upper and free ends of the limbs of the spring 10 are inclined or bent outwardly so as to diverge upwardly as at *d* and the terminals of the limbs are bent inwardly or convergingly as at *e*. On the application of the lid to the box, the spring is assembled with the lid by 15 turning it so that its limbs are parallel with the head of the button, as shown in dotted lines in Fig. 1, then slipping the limbs over the button, then rotating or turning the spring at a right angle to the head of the button, as shown in Fig. 1, there being sufficient 20 clearance between the button and lug 23 for this purpose, and finally compressing the ends to enter the groove between the faces *a* of the shoulders 15. In the assembled position 25 the ends of the head of the button overlap the opposite limbs of the spring which are under tension between the shoulders.

On the outer faces of the side walls of the box are lugs 25 which are beveled at their 30 rear faces, as at 26, and are designed to be engaged by rearwardly extending hooks 27 on the lid to hold the lid in locked position.

When the lid is in closed position the hooks 27 engage the lugs 25 as shown in Fig. 4, the 35 converging ends *e* of the spring reacting against the cam faces *a*, and as the limbs of the spring are then under tension, they press the lid downwardly and hold the same firmly to its seat. To open the lid the latter is slid 40 upwardly far enough to clear the hooks 27 of the lugs 25, and in this position the point of the shoulder 14 will be in the line of the circle of the pintle 18. The lid is now swung outwardly turning the pintle so that it rides 45 on the shoulder 14, as shown in dotted lines in Fig. 2, the curvature of the hinge lug and also the cam shoulders 15 then being substantially concentric with the hinge pintle. During this initial movement the converging 50 ends *e* of the spring are passing the cam faces *a* which due to the coöperation of the parts force the limbs of the spring toward each other and put them under greater tension. As soon as the junctures of the angular portions 55 of the limbs of the spring pass the crowns of the cam faces *a* and *b*, the limbs will react against the divergingly disposed cam faces *b* and cam the spring and consequently the lid into its open position, as shown 60 in Fig. 3, in which position it is held by the coöperation of the cam faces *b* with the angular portions *d* of the spring. In closing the lid the latter is swung downwardly on its pivot until the hooks thereof rest on the lugs 65 25, as shown in dotted lines in Fig. 2, the lid

is then pushed rearwardly, and as soon as the hooks pass beyond the upper faces of the lugs the inwardly converging ends *e* of the spring which have been drawn down over the crowns react against the cam faces *a* and will be cammed downwardly sliding the lid into its closed position. With this arrangement 70 it will be seen that while the initial opening movement of the lid is performed manually the final opening movement is performed automatically by the coöperation of the spring with the cam faces *b*. In closing the operation is manual until the hooks clear the lugs when the final closing movement is performed by the cam faces *a* and coöperating 75 ends *e* of the spring. 80

The arrangement of the cams and spring may obviously be reversed, as shown in Fig. 5. In this figure the hinge lug 12 is provided with a central shoulder 28 having the cam 85 faces *a'* and *b'*, corresponding to the cam faces *a* and *b*, respectively, of Fig. 1, located at the sides thereof. With this arrangement, the portions *d'* of the spring are bent inwardly and the terminal portion *e'* bent outwardly. The operation is the same as that heretofore described. 90

In Fig. 6 I have shown a modification in which the locking lugs and hooks are omitted. In this construction the hinge opening 29 is 95 circular and the hinge pin is also circular in cross section. Except for these changes the construction may be the same as that heretofore described. With this arrangement the movement of the lid is performed manually 100 until the angles of the spring pass the crowns of the cams *a* and *b*, when the lid is automatically thrown to its full open position by the coöperation of the angular portions *a* of the spring limbs with the cam faces *b*. In 105 closing the lid, as soon as the angles of the spring pass the crowns of the cams, the lugs 25 being omitted, the lid is closed automatically and does not have to be pushed inwardly as is necessary when such lugs are employed. 110 It is obvious that the spring may consist of a single limb instead of a pair in which case only one pair of cam faces *a* and *b* need be employed. Such single limb may be secured to the lid by bending its lower extremity 115 around the button shank, as shown in Fig. 7. I prefer, however, to employ the two limbed spring, as the limbs acting in opposition to each other serve to balance the lid and prevent tilting of the hinge pin. 120

By reason of the arrangement described, the spring may be readily replaced in the event that it becomes broken or unduly weakened, and in such case it is only necessary to remove the lid and turn the spring so 125 that it will slip off the button.

Having described my invention what I claim, is—

1. The combination with a journal box having a hinged lid, of cams fixed to the box, 130

and a U-shaped spring carried by the lid and coöperating with the cams to move the lid into and hold it in its closed position.

2. The combination with a journal box 5 having a hinged lid, of opposing cam faces on the box, and a U-shaped spring having angular ends coöperating with the cams.

3. The combination with a journal box having a hinge-pin lug, of a lid having its hinge-pin journaled in the lug, shoulders on the lug having two pairs of opposing cam faces, one pair of such cam faces being arranged divergently and the other convergently, a U-shaped spring carried by the lid and the ends of which coöperate with one pair of cam faces to swing the lid into its closed position and with the other pair of cam faces to swing the lid into its open position.

20 4. The combination with a journal box having a hinge-pin lug, and a lid having a hinge-pin pivoted in the lug, of oppositely disposed shoulders concentric with the turning center of the lid and provided on their adjacent sides with opposed pairs of cam faces, one pair of which converges upwardly and the other pair of which diverges from the upper ends of the first pair, and a U-shaped spring carried by the lid the limbs of such 25 spring having angular ends which when the lid is in one position react against the converging pair of cam faces to close the lid and when the lid is in another position react against the other pair of cam faces to throw the lid to its full open position.

30 5. The combination with a journal box, of a lid having a hinge-pin pivoted on the box, the hinge pin opening having a hinge-pin support with which such pin is out of engagement when the lid is closed, and the opening being elongated to permit of sliding of the lid upwardly so that the pin will ride upon the pin support when the lid is swung open.

35 6. The combination with a journal box having a hinge-pin lug the opening of which is provided with a shoulder, of a lid having a hinge-pin in the opening normally out of engagement with the shoulder, the said opening being elongated vertically to permit of sliding movement of the lid so that the pin will ride on the shoulder when the lid is swung to open or close the lid.

40 7. The combination with a journal box having a hinge-pin opening, of a lid having a hinge-pin in the opening, lid locking means disengaged by sliding movement of the lid, and a bearing in the hinge pin opening with which the pin is normally out of engagement but upon which the pin rests and turns after 45 the locking means are disengaged.

45 8. The combination with a journal box having a vertically elongated hinge-pin opening provided with an angular shoulder, of a lid having a hinge-pin in the opening, such 50 pin having a segmental recess which strad-

dles the shoulder when the lid is closed, lugs on the box, and lug engaging hooks on the lid which are disengaged from the lugs by sliding movement of the lid which movement elevates the pin so that the latter will 70 ride upon the shoulder when the lid is swung on its pivot.

9. The combination with a journal box having a vertically elongated opening and provided with opposing cam faces, a lid having a fixed pin located in the opening, locking lugs on the box, and coöperating hooks on the lid disengaged from the lugs by vertical sliding movement of the lid, of a U-shaped spring carried by the lid and the ends 80 of which react against the opposing cam faces to slide the lid downwardly to engage the hooks with the lugs and close the lid.

10. The combination with a journal box having a hinge-pin lug provided with a vertically elongated opening, the box being provided with a lower pair of opposing cam faces converging upwardly and a reversely arranged pair of cam faces extending upwardly from the first mentioned pair, a lid 85 having a hood inclosing the cams and provided with a hinge-pin in the opening, locking lugs on the box, and coöperating hooks on the lid which are disengaged from the lugs by sliding movement of the lid, of a U- 90 shaped spring secured in the hood and having angular ends which when in engagement with the lower cam faces and the lid is partially closed slides the lid downwardly to move the hooks into locking engagement with 95 the lugs and when in engagement with the upper cam faces throw the lid into full open position.

11. The combination with a journal box having a hinge-pin lug provided with a vertically elongated opening and a hinge-pin support at the lower end of the opening, of a lid having a recessed hinge pin in the opening straddling the support, locking lugs on the box, and lug-engaging hooks on the lid which 100 are disengaged from the lugs by a vertical sliding movement of the lid which movement elevates the hinge pin so that when the lid is swung the pin rides on the support, shoulders on the hinge-pin lug concentric 105 with the axis of the pin in its elevated position, upper and lower pairs of opposing cam faces on the adjacent sides of the shoulders, and a U-shaped spring carried by the lid, the ends of which react against one pair of opposing cam faces to slide the lid downwardly 110 to engage the hooks with the lugs and react against the other pair of cam faces to throw the lid into and hold it in its open position.

12. The combination with a journal box 115 having a hinged lid, of a removable spring carried by the lid and adapted to be engaged therewith by rotary movement in a plane parallel with the face of the lid.

13. The combination with a journal box 120

lid having a button on its inner face, of a spring for holding the lid in closed position and adapted to be engaged and disengaged from the button by movement of the spring 5 on the button as its axis.

14. The combination with a journal box, having a cam thereon, and a lid hinged to the box, of a spring for holding the lid in closed position, and a button on the lid with which 10 the spring is adapted to be engaged by a rotary movement of the spring on the button.

15. The combination with a journal box having opposing cams, and a lid hinged to the box, of a U-shaped spring the free ends 15 of which extend vertically and coöperate with the cams to maintain the lid in closed position, a button on the lid having a shank curved transversely on its under face and straddled by the spring, said spring being

adapted to be engaged with the button by 20 slipping the same over the button and then turning the spring to its vertical position, and a lug under the button shank and having its upper face concentric with the curvature of the shank on which the spring rests. 25

16. The combination with a journal box having a hinged lid, of cams on one of the parts and a U-shaped spring on the other part coöoperating with the cams to move the lid into and hold it in its open and closed positions. 30

In testimony whereof I affix my signature in presence of two witnesses.

JOHN PEARSON.
